UNITED STATES PATENT OFFICE.

OLAF E. MOGENSEN, OF PLAINFIELD, NEW JERSEY, ASSIGNOR TO F. L. SMITH & CO.,
OF NEW YORK, N. Y., A CORPORATION OF NEW JERSEY.

TUBE-MILL.

1,115,715.

Specification of Letters Patent.

Patented Nov. 3, 1914.

Application filed March 21, 1912. Serial No. 685,308.

To all whom it may concern:

Be it known that I, OLAF E. MOGENSEN, a citizen of the United States, residing in Plainfield, Union county, State of New Jersey, have invented certain new and useful Improvements in Tube-Mills, of which the following is a specification, reference being had to the accompanying drawings, which form a part hereof.

10 This invention relates to tube mills which are divided transversely to form two chambers for the reception of grinding bodies of different kinds, flint pebbles being usually placed in the chamber at the feeding end of the mill and small grinding bodies in the chamber at the discharge end of the mill. The partition which separates the chambers is usually slotted or otherwise perforated so as to permit the material which has been 15 reduced in the chamber with the flint pebbles to pass through the same into the other chamber, the slots or other perforations being so narrow or small as to prevent the smaller grinding bodies from passing backward through the same into the first chamber.

It is found that perforated partitions wear out rapidly and it is the object of this invention so to improve the construction of 20 tube mills of this character as to maintain the separation between the two chambers, permit the passage of the reduced material from the first chamber to the second, and prevent the movement of the smaller grinding bodies from the second chamber to the first without the use of the transverse perforated partitions such as have been employed hitherto.

In accordance with the invention the mill 25 is provided with an imperforate partition between the chambers and circumferential channels are provided such that the passage of the reduced material from the first chamber to the second is permitted while the passage of the smaller grinding bodies from the second chamber back to the first is prevented.

The invention will be more fully explained hereinafter with reference to the accompanying drawings in which are illustrated several embodiments of the invention and in which—

Figure 1 is a view in longitudinal section of so much of a tube mill, equipped with the invention, as is necessary to enable the in-

vention to be understood. Fig. 2 is a view in section on the plane indicated by the line 2—2 of Fig. 1, looking in the direction of the arrows. Figs. 3 and 5 are views similar to Fig. 1 but showing slightly different embodiments of the invention. Figs. 4 and 6 are views in transverse section on the planes indicated by the lines 4—4 and 6—6 of Figs. 3 and 5 respectively. Fig. 7 is a developed circumferential section of the circumferential channels shown in Figs. 5 and 6. Fig. 8 is a developed circumferential section, in detail, illustrating still another arrangement of the channels. Fig. 9 is a detail view in longitudinal section through a portion of a tube mill, with the channels arranged as shown in Fig. 8. Figs. 10 and 11 are views in longitudinal and transverse section respectively illustrating a further modification.

The tube mill to which the invention is applied may be of any usual or suitable construction and is shown in the several figures of the drawings as comprising a cylindrical metal shell *a* provided with trunnions *b*, and suitable wear resisting lining *c*, and grated discharge openings *d* for the discharge of the pulverized material. The material to be pulverized is fed to the mill through convenient openings *e* 85 which may be formed in the trunnions *b* and in which may be suitable feed mechanism here illustrated as a screw and the grinding bodies are introduced into the chambers *f* and *g* through any suitable door 90 as usual in mills of this description. At a suitable point within the mill is secured in any suitable manner an imperforate partition *h*, preferably nearer the discharge end than the feed end, so that the chamber *f*, in which are placed the flint pebbles, is considerably larger than the chamber *g* in which are placed the smaller grinding bodies. In the wall of the cylinder, in the chamber *f* but adjacent to the partition *h*, 100 are provided discharge openings *i*, and in the wall of the mill, but in the chamber *g* and adjacent to the partition *h*, are formed grated openings *k* through which the material reduced in the chamber *f* is discharged into the chamber *g*. The openings *i* are connected with the openings *k* by troughs or conduits forming channels which are so arranged as to conduct the reduced material from one chamber to the other and 110

to prevent the return of the smaller grinding bodies from the second chamber to the first. These channels may be arranged in many different ways to accomplish this result, several different arrangements being shown in the several figures of the drawings.

Referring first to the arrangement of the channels shown in Figs. 1 and 2 it will be seen that there are applied to the outer wall of the shell *a* circumferential channel casings *l* which cover several of the openings *i* and communicate with a single opening *k*, there being several discharge openings *i* 15 for each inlet opening *k*. Each such channel casing is carried from the openings *i* to the opening *k* in a direction opposite to the direction of rotation of the cylinder. Therefore the material which enters the 20 channel through the grated openings *i* is carried through the channel, in the rotation of the shell and passes into the chamber *g*, while such grinding bodies as may in any way find their way into the channel 25 from the chamber *g* are returned at once, in the continued rotation of the mill, to the chamber *g*.

In the arrangement shown in Figs. 1 and 2 the casings *l* are independent, one of another, but in the arrangement shown in Figs. 3 and 4 the casing *l'* which covers the openings *i* is continuous around the circumference of the shell and is provided at intervals with deflecting plates *l''* which direct the material received through the corresponding openings *i* to a branch channel formed by a branch casing *l'''* through which the material passes to the corresponding opening *k* in the chamber *g*.

In the arrangement shown in Figs. 5, 6 and 7 the casing *l'* is continuous circumferentially and covers the openings *i* and *k*, being provided with internal partition plates *l''* which form the channels from each 45 group of openings *i* to the corresponding single opening *k*. In this case the openings *k* are shown as covered by hoods *l'''* which continue the channels in the same direction, the hoods being open at their 50 ends.

In the several arrangements already described the channels through which the material is directed from the openings *i* to the openings *k* are formed by exterior 55 casings, but when the improvement is applied to old machines, in which it may be difficult to cut the openings in the shell, the

channels may be formed wholly within the shell, the lining of which is removed circumferentially so as to permit the continuous casing *l'* to be placed within the shell, as shown in Fig. 9. The casing *l'* then has the openings *i'* and *k'* formed therein and is provided with partition plates *l''* which form the channels by which the material *i'* is directed from the openings *i'* to the openings *k'*.

In the arrangement shown in Figs. 10 and 11 the openings *i* and *k* are formed in the shell *a* as before and are covered by an exterior casing *l'* provided with partitions *l''* to form the channels as shown in Figs. 5, 6 and 7. The material is discharged through the openings *k*, however, not directly into the chamber *g*, as before, but into narrow chambers *m* which are formed by radial plates *m'* between the imperforate partition *h* and a secondary partition *m''*. The latter is provided with a central opening *m'''*. A cone *m''''* is secured centrally to a partition *h* and directs the material from the several chambers *m* through the central opening *m'''* into the chamber *g*.

Various other arrangements will suggest themselves, as the conditions of use require.

I claim as my invention:—

In a tube mill, the combination of a rotatable shell, an imperforate transverse partition therein, said shell having a series of discharge openings at one side of said partition and a series of inlet openings at the other side of said partition, independent circumferential channel casings of relatively great length applied to the outer wall of the shell, each of said casings covering several of the discharge openings to receive the material directly from the shell and communicating with a single inlet opening and being extended substantially spirally and uninterruptedly from said discharge openings to said inlet opening, respectively in a direction opposite to that of the direction of rotation of the shell, whereby the return of material from each of said inlet openings to the respective discharge openings is automatically prevented and the free and uninterrupted flow of material facilitated.

This specification signed and witnessed this 12th day of March A. D., 1912.

OLAF E. MOGENSEN.
